Specification for Design.

Patented Nov. 9, 1920.

Application filed May 10, 1918. Serial No. 233,812. Term of patent 3½ years.

To all whom it may concern:

Be it known that I, BERNIE BROOKS, a citizen of the United States, residing at the city of St. Louis and State of Missouri, have invented a new, original, and ornamental Design for a Collar-Fastener, of which the following is a specification, reference being had to the accompanying drawing, forming a part thereof.

In the accompanying drawing in which I have illustrated my new design—

Figure 1 is a plan view.

Fig. 2 is a side elevation.

Fig. 3 is an end elevation.

I claim:

The ornamental design for a collar fastener, substantially as shown.

In testimony whereof I have hereunto set my hand this 15th day of April, 1918.

BERNIE BROOKS.
